UNITED STATES PATENT OFFICE.

HERBERT C. WILLIAMSON, OF NEW YORK, N. Y.

ROTARY SNAP-SWITCH.

No. 893,688.

Specification of Letters Patent.

Patented July 21, 1908.

Application filed May 18, 1906. Serial No. 317,475.

To all whom it may concern:

Be it known that I, HERBERT C. WILLIAMSON, a citizen of the United States, and a resident of New York city, in the county of 5 New York and State of New York, (whose post-office address is 203 West Fifty-second street, New York city, New York,) have invented certain new and useful Improvements in Rotary Snap-Switches, of which the 10 following is a full, clear, and exact description, whereby any one skilled in the art may make and use the same.

The invention relates to snap-switches and more particularly to the type of device commonly known as rotary snap switches. The arrangement is such that the contact making and breaking elements revolve to make or disrupt the circuit between the fixed terminals of the circuit.

20 The object of the invention is to provide a simple, inexpensive and compact device, all of the several parts working with precision and under positive impulse.

A further object is to provide a device, the 25 several elements of which may be formed from sheet metal pressed up to give a very rigid structure.

A still further object is to provide a device in which there will be a positive ratchet and 30 pawl action for locking and releasing the rotary parts upon a positive tensioning of a quick acting make and break device.

A still further object is to provide for positive though resilient control of the pawl with 35 reference to the ratchet to assure proper interlocking of the parts.

Referring to the drawings: Figure 1 is a 40 plan view of the switch with the cap removed. Fig. 2 is a cross-sectional view. Fig. 3 is a general view of the various parts unassembled and shown in perspective to better illustrate the several elements.

In the accompanying drawings the numeral 1 denotes a base of suitable insulating material 45 provided with stationary contacts and necessary conductors, with provision for attaching line wires of a circuit. The base, also, has a suitable cover 2 which incloses the various parts of the mechanism and protects them 50 from short circuit and injury.

Suitably mounted with reference to the base 1 and fixed against rotation with reference thereto, is a ratchet 3 provided with a hub 4 and a central opening 5 through which 55 a spindle 6 projects and is free to turn though held against axial movement by a pin 28

passed through the spindle below the ratchet. The ratchet forms a bearing for the spindle and various rotary parts hereinafter defined. This ratchet has openings 7, the number and arrangement of which will be dependent upon the type of switch made for any particular service. As shown herein, there are four ratchet openings. The periphery of the ratchet between each of the succeeding 65 ratchet openings is cut back toward the center, thus providing a high striking tooth 8, against which the pawl will impinge when released, for a forward movement. That is, with the pawl in any ratchet opening the 70 wall of said opening in advance of the pawl is of a considerable height while the wall at the rear face is comparatively low. In fact, it is just sufficient to prevent retrograde or backward movement of the pawl. 75

Loosely mounted upon the spindle 6 is a contact actuating plate 9 which may be of any appropriate form, and has secured to it the movable contact blade 10 which makes and breaks the electric circuit as it is passed 80 into and out of contact with the stationary contacts of the base. The contact blade 10 while fixed to and moving with the contact actuating plate 9 is insulated therefrom and from the spindle 6 by an insulating bushing 85 20 and washer 21, the several parts being suitably pressed or clamped together to form practically an integral structure.

Pivoted arranged in the plate 9, as at 11^a, 90 is a pawl 11 and, as shown herein, the contact actuating plate 9 is formed of two pieces of sheet metal secured together with a space between them, while the pawl 11 is also formed of sheet metal and is pivoted between the plates of the contact plate 9 as at 95 11^a. Of course, it is understood that the contact bar 10 is thoroughly insulated from the various elements of the structure by the washers and bushings, heretofore indicated.

A releasing cam or lug 12 is secured to the 100 spindle and lies in position to be rotated against a projecting releasing lug 13 formed by upsetting a portion of the pawl plate 11. It will be noted that the releasing cam or lug 12 is mounted upon the spindle while the 105 pawl plate 11 is pivoted to the plate 9 and, therefore, is pivoted eccentrically with reference to the spindle. It follows that a rotation of the cam 12 swings the pawl 11 upon its pivot 11^a as the cam surface 12^a presses 110 against the lug 13 of the pawl plate and as the end of the cam 12^a adjacent to the lug

12^b engages the lug 13, the tooth 14 of the pawl 11 is disengaged from the tooth of the ratchet 3. Thereupon the spring 16 forces the contact bar 10 and contact actuating plate 9 forward until the pawl tooth 14 engages the next succeeding ratchet opening 5 of the ratchet 3. There is also an upturned lug 15 upon the pawl which forms an abutment against which one end of a spring 16 10 rests. This spring 16 is coiled about the spindle 6, one end being secured thereto, while the other end 16^a bears against the upturned lug 15 of the pawl 11 and normally presses the tooth 14 of said pawl 11 into engagement 15 with the peripheral openings and peripheral surface of the ratchet. Its action is such as to compel the tooth 14 to ride along the surface of the ratchet intermediate the peripheral openings, and as it is released from 20 one ratchet tooth to engage the next succeeding ratchet tooth. Thus the spring has a double function. In addition to controlling the position of the pawl, it serves as a tensioning spring for quickly moving the contact plate 9 with its attached contact 10, and insures control of the pawl 11 during the free 25 flying movement of the various parts.

It will be seen from the above described arrangement that a single spring intermediate 30 the spindle and contact actuating plate, provides for controlling the pawl and ratchet in their engaging and disengaging movements, and provides the necessary power for driving the switch-bar to secure a quick make 35 and break.

There can be no uncertain movement of the contact bar such as is often present in devices of this class. It must be moved in a predetermined manner and to exact distances. Therefore, the proper making and breaking of the circuit through the engagement and disengagement of the contact bar 10 and the stationary contacts, is assured. This movement is dependent upon the arrangement 40 of the pawl and the ratchet.

To provide against backward movement of the cam plate 12 and consequently a backward movement of the switch spindle 6, a lug 26 is provided on the actuating contact plate 50 9. This lug 26 lies at the rear of the cam 12 and acts as a stop for said plate through the medium of the lug 12^b which bears against it. The spring 16 is normally under some tension when in engagement with the lug 15 of the 55 pawl 11 and as the tooth 14 is thus forced into one of the ratchet openings and the lug 26 lies in the rear of the lug 12^b the cam plate 12 is positively locked against retrograde movement. It will thus be seen that 60 the various parts are positively locked against backward or forward movement until the cam plate 12 is rotated to release the

pawl tooth 14 from the engaged ratchet tooth. The pawl is always firmly held in the tooth recess of the ratchet until positively released by said cam 12. This cam, of course, forces the tooth of the pawl from engagement with the ratchet teeth, and immediately upon the release of the ratchet teeth and pawl, the plate 9 with its pawl plate 11 is rotated by the spring 16; said spring forcing the tooth 14 into close contact with the ratchet as soon as the plate and tooth run away from the cam 12. With this arrangement there is little or no backward pressure upon the spindle or handle 27. It is of course, apparent that the rotation of the cam 12 tensions the spring 16 to a sufficient degree to cause a quick forward flying movement of the contact bar 10 and appurtenant parts as soon as the pawl 14 is moved out of engagement with one of the ratchet teeth.

Obviously, the various parts of the mechanism might be varied in design and arrangement to a considerable extent without departing from the spirit or intent of the invention, and various forms of ratchet might be used with provision for contact bars, giving a single or double pole switch.

What I claim as my invention and desire 90 to secure by Letters Patent is:

1. In combination in a snap switch, a base of insulating material, a ratchet secured in said base and providing a bearing for a spindle, said ratchet having peripheral openings, a spindle mounted in said ratchet and provided with a releasing cam, a contact actuating plate loosely mounted on the spindle, a pawl pivoted to said contact actuating plate and provided with a tooth to engage the ratchet openings, a stop upon the contact actuating plate to prevent backward movement of the spindle and a spring normally under tension secured to the spindle and bearing against one end of the pivoted pawl. 105

2. In combination in a snap switch, a base of insulating material, a ratchet mounted therein and provided with openings, one wall of which extends a greater distance from the center than the other, a contact actuating plate formed from sheet metal and provided with a stop lug to engage a releasing cam, the releasing cam secured to the spindle, a pawl formed from sheet metal and provided with a cam lug, a spring lug and a pawl tooth and a spring normally under tension with one end secured to the spindle and the opposite end in engagement with the spring lug of the pawl. 110 115
